UNITED STATES PATENT OFFICE.

NICHOLAS A. McMANUS, OF NEW YORK, N. Y., ASSIGNOR TO ITHACA WALL PAPER MILLS, A CORPORATION OF NEW YORK.

DESIGN FOR WALL-PAPER.

SPECIFICATION forming part of Design No. 35,736, dated February 11, 1902.

Application filed January 10, 1902. Serial No. 89,241. Term of patent 3½ years.

To all whom it may concern:

Be it known that I, NICHOLAS A. McMANUS, a citizen of the United States, residing at New York city, in the county of Richmond and State of New York, have invented and produced a new and original Design for Wall-Paper, of which the following is a full, clear, and exact specification.

The figure shown on the drawing is a plan view of my new design for wall-paper, showing it adapted to be used in a border.

As shown in the drawing, the leading or material feature of my design consists of the main panel 1 and the subordinate panels 2. Only a half of each of the subordinate panels is shown, but these halves are complements of each other. The main panel is placed between the subordinate panels.

The main panel 1 consists of the fleur-de-lis 3 and clusters of flowers 4, surrounded and supported by scrollwork 5. Lines of conventionalized flowers 6 and scrollwork 7 surround the main panel.

Each of the subordinate panels consists of the clusters of flowers 8, surrounded and supported by the scrollwork 9. Lines of conventionalized flowers 10 and scrollwork surround the subordinate panels. A chain of conventionalized flowers 11 and scrollwork 12 connects the two subordinate panels and passes beneath the main panel. Festoons of flowers 13 are looped from the chain 11 12.

Having thus described my invention, I declare that what I claim as new, and desire to secure by Letters Patent, is—

The design for wall-paper as herein shown and described.

In testimony whereof I affix my signature in presence of two witnesses.

NICHOLAS A. McMANUS.
